UNITED STATES PATENT OFFICE.

GEORGE E. ADAMS, OF NEW BRITAIN, CONNECTICUT.

DESIGN FOR A METALLIC MEMBER FOR GARMENT-SUPPORTERS.

SPECIFICATION forming part of Design No. 33,635, dated December 4, 1900.

Application filed November 3, 1900. Serial No. 35,423. Term of patent 7 years.

To all whom it may concern:

Be it known that I, GEORGE E. ADAMS, a citizen of the United States, residing at New Britain, in the county of Hartford and State of Connecticut, have invented and produced a new and original Design for a Metallic Member for a Garment-Supporter, of which the following is a specification, reference being had to the accompanying drawings, forming part thereof.

In the accompanying drawings, Figure 1 is a face elevation of a metallic member or connecting member for a garment-supporter embodying my present design. Fig. 2 is a top plan view of the same.

The leading or characteristic features of the present design are the body member having an elongated loop at its lower edge, two vertical tubular loops, one at either side, and one horizontally-arranged tubular loop centrally at the top of said body portion.

Referring to said drawings, the letter A indicates the body of the member, B the elongated loop extending along the lower edge of said body, and C C two vertically-arranged tubular loops, one at each side or end of the body, said last-mentioned loops having edge flanges c and circular extensions D D at their junction with the body portion A.

The letter E indicates the central horizontally-arranged loop above the body, which loop E has edge flanges e and a circular base F at its point of junction with the body A.

I claim—

The design for a metallic connecting member of a garment-supporter herein shown and described.

GEORGE E. ADAMS.
